UNITED STATES PATENT OFFICE.

MIGUEL ESCUDER AND ANTONIO FOREST, OF BARCELONA, SPAIN.

EMBROIDERING-MACHINE.

SPECIFICATION forming part of Letters Patent No. 749,044, dated January 5, 1904.

Application filed June 10, 1902. Serial No. 111,080. (No model.)

To all whom it may concern:

Be it known that we, MIGUEL ESCUDER and ANTONIO FOREST, residing at Barcelona, in the Province of Barcelona and Kingdom of Spain, have invented certain new and useful Improvements in Embroidering-Machines; and we do hereby declare the following to be a full, clear, and exact description of the invention, such as will enable others skilled in the art to which it appertains to make and use the same.

Our invention relates to improvements in embroidering-machines in which vertically-reciprocating needles operate in conjunction with horizontally-reciprocating lugs; and the objects of our improvements are to provide means for the threads to be changed from one needle to another in order that every stitch may be made with a different thread or the thread may vary for a number of stitches, thus rendering it possible to combine a great number of designs which may be varied at will. To attain this object, our improved machine is fitted with the following devices: A plurality of needles formed with a spring-hook at their upper ends, which opens at the rear part thereof, said needles being disposed to be vertically reciprocated in such a manner that at their upper position the hooks remain open to catch the threads, and at their downward movement each needle-hook strikes on the beveled flange of the fixed guide-plate, whereby the hooks are closed when the needles pass down through the fabric. Over said needles a plurality of loopers are suitably disposed to execute two different movements—viz., a forward and backward motion through or between the series of needles and a lateral or right and left motion, whereby the loopers may run the distance between two or more needles. The motion is imparted to the loopers, so that the threads may change from one needle to another and that the threads may be passed in the needle-hooks accordingly to the design to form the desired stitches. Each needle makes a series of knitting-strokes disposed in a right line, so that if the machine has two, four, six, eight, or ten needles it will execute two, four, six, eight, or ten series of knitting-strokes. As the needles are threaded and unthreaded at every

stitch and as the threads by their lateral motion may change from one needle to another, it is obvious that every stitch may be made in a different color or the colors may vary for a number of stitches, thus rendering it possible to combine a great number of designs which may be changed at will. The cloth or fabric to be embroidered runs forward at every stitch by means of a lower clamp-bar so operated as to move the fabric forward in a similar manner as is common in sewing-machines.

In the accompanying drawings we represent our new embroidering-machine having ten needles and twelve lugs.

Figure 1 is a front elevation of the machine. Fig. 2 is a plan thereof. Fig. 3 is a vertical section on line *zz* of Fig. 1. Figs. 4, 5, 6, and 7 are detail sections, at an enlarged scale, showing the different positions of the needles and lugs to form the stitches.

The needles 3 are formed with a point 3' at their upper end, which forms a spring-hook 3", wherein the thread is passed. The lower end of the needles is bent at right angles, thus forming a tail whereby the needles are strongly secured to the needle-holder.

The needle-holder consists of a metal plate 8, sliding between vertical guides 7 and formed with longitudinal grooves to receive the needle-shanks and with horizontal transverse holes to insert the needle-tails, so that the needles are held at the proper position and at an exact distance apart from each other and are firmly secured in place by means of a guard-plate 5.

The lower end of the guard-plate 5 is connected by means of an elastic sheet 10 to a lever 25, which operates the vertically-reciprocating plate 6 and causes the needles to go first up through the fabric and rest before the threads are threaded in the needle-hooks and then down through the fabric to form the stitches.

The elastic sheet 10, connecting the plate 6 to the lever 25, is formed with enlarged holes, whereby the level of the needles is exactly determinate and secured. The lever 25 oscillates on pin 8 by means of a rod 9, connected to an intermediate point of said lever and secured to or forming a casting with an eccentric 9', mounted on shaft 45, whereby a

reciprocating motion is imparted to the lever 25, and consequently to the needles.

Shaft 45 is formed with a cam 9", against which an angle-bar 28 bears, thus causing 5 the clamp-bar 27 to move forward and backward in such a manner that the toothed part 11 thereof may push the fabric forward at each stitch.

The clamp-bar 11 27 is supported by an 10 angle-bar 28, and its position is regulated by a screw 29. The rear end of said clamp-bar 27 bears on a pin 30, which serves for a guide when it moves to and fro. The spring 31 tends to replace the clamp-bar 27 to its original position.

Loopers 4 are formed of metal rods provided with an eye at their lower flattened ends and with a tail at their upper extremities. They are firmly secured between plates 20 4 and 4', provided with longitudinal grooves to receive the lugs, so that they are held from each other at exactly the same distance as are the needles 3. The guard-piece 4' is secured by a screw to a plate 4", which carries 25 two little ribs 32 and 32' with holes to pass and guide the threads. Plate 4" is further provided with an arm 15 and friction-roller 15', bearing on cam 34 and constantly acted upon by a spring 33, which tends to throw 30 the roller 15' against the cam.

The plate 4" may vertically oscillate and longitudinally slide upon the shaft 12, properly supported on bearings 12' on the frame 1 of the machine. Said bearings 12' support 35 also another shaft 13, placed behind shaft 12 and carrying a cam 13', formed with a cam-groove 13", engaging the friction-roller 15' of arm 15 of the plate 4". The pitch of said cam-groove is so calculated as to force the 40 loopers 4 to run from one side to another side of the needles to thread them on. Cam 34 moves so that it forces the loopers 4 to oscillate and run from the front to the back of the needles, so as to permit the threads to be 45 passed round the needles and to be caught by the needle-hooks after entering therein by the lower opening thereof.

Besides the several motions hereinbefore stated for the plate 4" and loopers 4 a further 50 motion is imparted thereto by shaft 13 by means of the cam 13' and arm 14, which forces the plate to run lengthwise on shaft 12 in order to change the position of the loopers, respectively, to that of the needles, whereby it 55 becomes possible to change at will at any moment the threading of each needle.

Shaft 13 bears on a slide 35, having a roller 35' and sliding on a rod 36, while the roller 35' is operated by a chain 38, provided with 60 bosses or blocks 38', suitably mounted thereon. Thus the shaft 13, the cam 13', and the loopers 4 are so moved that each needle may be threaded on with the thread of the desired loopers. Rotary motion is imparted to the 65 shaft 13 by means of the gear-wheels 44, 43, and 42, the latter being mounted on shaft 45, which bears the driving-pulley 41.

A ratchet-wheel 37 is fixed on the same shaft supporting the chain-wheel 38, the pawl 39 thereof being hinged to the inner part of 70 a slide 22, provided at both ends with rods 22', traveling in bearings 23 and 23', secured to the frame of the machine. Rigidly secured to the upper rod 22' is a ring or die 24, which by means of a pin 24' is connected to 75 the upper end of a vertical side link 40, connected by its lower end to the fork 46' of a horizontal rod 46, having an arm 53 with a friction-roller 53' bearing on a cam 54. This cam pushes the roller 53', links 46 and 40, 80 and pawl 39 upward and causes the ratchet-wheel 37 to revolve the distance of one tooth. A spring 26 constantly pushes the pawl 39 toward the ratchet-wheel 37, which when revolved is prevented turning more than the 85 necessary distance by means of a brake composed of an elastic strip 55, secured to the shaft of the wheel by a screw 55' and provided at both ends with a packing 55".

The length of the chain 38 as well as the 90 size and shape of the chain-blocks 38" may vary at will in order to combine a great number of designs in the most convenient manner.

At the upper front part of the machine is a tension device or apparatus which is represented in front elevation in Fig. 1 and in vertical section in Fig. 2 of the accompanying drawings. Said apparatus is rigidly secured to the front part of the frame of the machine and consists of three revolving cylinders 46, 95 47, and 48, from which the middle one, 47, may be horizontally adjusted by the screws 51. The threads are passed before the cylinders 46 and 48 and behind the cylinder 47. Thus the tension of the threads is thoroughly 100 regulated at will, owing to the position of cylinder 47, respectively, to that of cylinders 46 and 48. Guide-bars 49 and 50 are also provided for the threads, which pass through further guides 20", 21, 32, and 32' before reaching 105 the lugs 4.

The several movements that the needles and loopers execute to form the stitches will be clearly understood by referring to Figs. 4, 5, 6, and 7 of the accompanying drawings. 110 Fig. 4 represents the needle 3 in its upmost position after having passed through the fabric 52, while the looper 4 is at the back before passing the thread around the needle. In Fig. 5 the needle 3 goes down while the 115 looper 4 has been already pushed forward, because of the movement imparted to the looper-holder by the operative cam 34, Fig. 3. When the thread 56 has once passed before the needle, the plate 4" is laterally displaced by 120 cam 13', which forces the threads to pass round the needles. Then the cam 34 forces the loopers 4 to go back again and recover their former position, as shown at Fig. 6. When the threads are passed round the needles, the 125 latter move downward and catch the threads, and the spring-hook 3" strikes against the beveled flange of the opening of the guide-plate 17, which closes the hook or eye of the 130

needle. Thus the hook when descending passes through the same hole bored by the needle-point at its first upward passage through the fabric. Fig. 6 represents the 5 needle when the needle-hook is closing to enable it to pass free through the fabric. Fig. 7 represents the needle in its lower position, after passed through the fabric, at the moment when the indented clamp-bar 11 27 pushes the 10 fabric forward in order that at the next upward movement of the needle a new stitch may be produced.

From the above description it will be seen that the needles are threaded stitch after 15 stitch, and consequently the threads passed therein may be changed at will at every stitch.

The press-bar 17, which holds the fabric against the clamp-bar 11 27 and against the fixed base-plate 2, is rigidly secured to an arm 20 17', carried by the rod 19, operated by cam 16, which may be rotated on a pin 16" to push against the pin 16' on said rod 19, whereby said arm and press-bar are lifted. The arm 17' is forked at one end to engage the bracket 25 18 of the frame, which serves as a guide for the arm 17' when it moves up and down.

Having thus described our invention, what we claim as new, and desire to secure by Letters Patent, is—

30 1. In an embroidering-machine, the combination of a main shaft, a plurality of needles reciprocated vertically by said shaft, a plurality of loopers pivotally mounted above said needles, tension mechanism for supplying thread to said loopers, cam mechanism connected to said loopers, whereby a horizontal oscillatory movement will be imparted to said loopers to form a loop upon each of said needles before its return movement, and 35 mechanism for shifting said loopers laterally, relatively to said needles.

2. In an embroidering-machine, the combination of a main shaft, a plurality of needles reciprocated vertically by said shaft, a 40 plurality of loopers pivotally mounted above said needles, tension mechanism for supplying thread to said loopers, cam mechanism connected to said loopers, whereby a horizontal oscillatory movement will be imparted to said loopers to form a loop upon each of said needles before its return movement, and 45 mechanism interposed between and coöperating with said main shaft and cam mechanism for automatically shifting said loopers relatively to said needles.

50 3. In an embroidering-machine; the combination of a plurality of needles, a support therefor, means for operating said needles, an elastic sheet connecting said support to said 55 operating means, loopers, cam mechanism for imparting an oscillatory movement to said

loopers, pattern mechanism for shifting said loopers laterally, and a pawl-and-ratchet mechanism for operating said pattern mechanism.

65

4. In an embroidering-machine, the combination of a plurality of needles, means for reciprocating said needles, loopers, mechanism for imparting an oscillatory movement to said loopers, and means for bodily shifting 70 said mechanism and said loopers laterally, substantially as described.

5. In an embroidering-machine, the combination of a plurality of reciprocating needles, loopers therefor, cam mechanism for oscillating said loopers, and means for bodily shifting said cam mechanism and said loopers in a lateral direction, substantially as described.

75 6. In an embroidering-machine, the combination of a plurality of needles, fabric-holding means, common means for reciprocating said needles and shifting said fabric, loopers for said needles, mechanism for operating said loopers, and means for bodily shifting 80 said operating mechanism and said loopers laterally, substantially as described.

7. In an embroidering-machine, the combination of needles, means for reciprocating the same, a series of loopers for said needles 85 loosely pivoted on a shaft, cam mechanism for operating said needles, a shaft to which said cam mechanism is secured, and means for laterally shifting said shaft thereby shifting said cam mechanism and said loopers.

90 8. In an embroidering-machine, the combination of cam mechanism, a shaft carrying said mechanism, and means for bodily shifting said shaft, consisting of a slide provided with a roller, pattern mechanism adapted to 95 contact with said roller, means for driving said pattern mechanism, and a spring for returning said shaft to its original position.

9. In an embroidering-machine, the combination of cam mechanism, a shaft on which 100 said mechanism is mounted, driving means for said shaft, means for shifting said shaft laterally, consisting of a slide provided with a roller, and pattern mechanism adapted to 105 contact with said roller, pawl-and-ratchet 110 mechanism for actuating said pattern mechanism, and connections between said pawl-and-ratchet mechanism and said driving means.

In witness whereof we have hereunto set 115 our hands in the presence of two witnesses.

MIGUEL ESCUDER.
ANTONIO FOREST.
